UNITED STATES PATENT OFFICE

120,455

DESIGN FOR A TEXTILE FABRIC

Frank Sudell, Roxborough, Pa., assignor to J. Harris Warthman, trustee for La France Industries, Philadelphia, Pa.

Application December 27, 1939, Serial No. 89,158

Term of patent 3½ years

To all whom it may concern:

Be it known that I, Frank Sudell, a citizen of the United States, residing at Roxborough, in the county of Philadelphia and State of Pennsylvania, have invented a new, original, and ornamental Design for a Textile Fabric, of which the following is a specification, reference being had to the accompanying drawing, forming part thereof.

The figure of the drawing is a plan view of the textile fabric showing my design.

I claim:

The ornamental design for a textile fabric, as shown.

FRANK SUDELL.
